Nov. 13, 1928.

1,691,790

S. VOLKER

GARMENT

Filed Jan. 31, 1927

Fig. 1

Fig. 2

Fig. 3

Inventor
Sylvia Volker
by Frank Schaefer Jr.
Attorney.

UNITED STATES PATENT OFFICE.

SYLVIA VOLKER, OF OAK PARK, ILLINOIS.

GARMENT.

Application filed January 31, 1927, Serial No. 164,699.

This invention relates generally to garments, but has particular reference to ladies' under garments adapted to be worn next to the body.

5 One of the objects of my invention is the provision of a unitary garment comprising a petticoat or skirt or "princess slip," a chemise or brassière and bloomers.

10 A further object of the invention is found in the particular construction of the garment herein shown wherein the three garments in one are supported from a single pair of shoulder straps, said construction embodying the securing or support of the upper portion 15 of the combined brassière and bloomers from the upper portion or upper end of the skirt or slip, thus carrying a double portion of the material above the waistline of the wearer and affording the use of the upper portion 20 of the bloomer garment as a chemise or brassière.

25 The upper chemise portion of the bloomer garment, as will hereinafter be explained is provided with a draw string or ribbon for tightening to afford the use of such upper garment portion as a brassière.

With the above and other objects in view, my invention consists in the novel combination and construction or arrangement of the 30 parts and members shown in the accompanying drawing, described in the following specifications and particularly pointed out in the appended claims.

Referring to the illustrations:

35 Figure 1 is an elevation of a garment embodying my invention with a portion thereof broken away to show an under garment;

Figure 2 is a cross section taken on line 2-2 of Figure 1, showing the junction of the 40 outer and inner garments;

Figure 3 is a cross section taken on line 3-3 of Figure 1, showing the draw string for the upper portion of the bloomer garment.

45 In the illustrations, 10 indicates a "princess slip" having a skirt or petticoat portion 10^A. The upper edge of the slip 10 is provided with a fold 11 which embraces the upper end or edge of the under garment 12, and securely retains same by a line of 50 stitches 13. The fold 11, it will be observed, is large enough to provide for the ribbon or cord 14 by means of which the upper part of the garment may be drawn together for close fit.

55 The under garment 12 comprises integral bloomers 12^A and an upper portion 12^B which may be worn as a chemise or as a brassière, by drawing of the ribbon or cord 15 which is provided in the pocket 16^A of the 60 band 16.

A single pair of straps 18 is provided which are sewed to the upper portion of the unitary garment.

Having thus described my invention, what 65 I claim as new and desire to secure by Letters Patent is:

1. A unitary fabric garment comprising an outer garment, means on the upper edge of said outer garment for drawing in said 70 upper edge for close fit on the wearer, a single pair of shoulder straps attached to the upper end of said outer garment, and inner garment, said inner garment being secured to said upper edge of said outer garment and the lower portion of said inner garment being formed into bloomers, a laterally extending pocket on said inner garment above the waist line and below the bust thereof, said outer garment extending downwardly 80 below the lower end of said bloomer portion, and a ribbon in said pocket for drawing in said inner garment below the bust of the wearer.

2. A unitary fabric garment comprising 85 an outer garment, and an inner garment, said outer garment having a fold at the upper edge thereof forming a laterally extending pocket, a single pair of straps secured to the upper end of the garment, said 90 inner garment having its upper edge secured to said upper edge of said outer garment, a ribbon or cord within said pocket of said outer garment whereby the upper ends of both outer and inner garments may 95 be drawn in for close fit on the wearer, means above the waist line and below the bust of said inner garment for drawing in said inner garment below the bust of the wearer, and a pair of bloomers formed on 100 the lower end of said inner garment, said outer garment extending downwardly below the lower end of said bloomer portion.

In witness whereof I affix my signature.

SYLVIA VOLKER.